UNITED STATES PATENT OFFICE.

HENRY JOHN SUTHERLAND MACKAY, OF ROSEMOUNT, ISLE OF WIGHT, ENGLAND, AS-
SIGNOR TO THE BABCOCK & WILCOX COMPANY, OF BAYONNE, NEW JERSEY, A COR-
PORATION OF NEW JERSEY.

STEAM GENERATOR.

Application filed September 4, 1918. Serial No. 252,515.

To all whom it may concern:

Be it known that I, HENRY J. S. MACKAY, a subject of the King of Great Britain, residing at Rosemount, Bellevue Road, Ryde, 5 Isle of Wight, in the county of Hampshire, England, have invented certain new and useful Improvements in and Connected with Steam Generators, of which the following is a specification.

This invention relates to marine boilers of the kind in which lower or mud drums are connected with an upper or steam and water drum or drums by inclined banks of tubes enclosing between them a furnace space, and has for its object generally to provide an improved construction thereof, in which the well known Stirling type of tubes arranged to enter the drums radially are employed.

My invention more particularly relates to a boiler of the above type in which provision is made for securing a definite path for the circulation of the water. In accordance with my invention, baffles are arranged within the steam and water drum which provide a steam liberating space in the middle of the drum, the feed water being admitted to the drum on either side thereof and without the baffles.

A further feature of my invention consists in the provision of transverse partitions within the mud drums, which, when used in conjunction with the baffles arranged in the manner above referred to, further promote the circulation of the water throughout the system. By providing the definite path of circulation in the manner described, which causes all of the steam to pass upward near the center of the drum, a uniform flow speed is secured between all of the tubes of a given row and difficulty through an irregular water action and swaying one way and the other of the water in the upper drums is eliminated.

In the drawings, Figure 1 is a side view of an A-shaped boiler embodying my invention; Fig. 2 is an end view, partially in elevation and partially in section, of the boiler of Fig. 1, and Fig. 3 is a view similar to Fig. 2, partially in end elevation and partially in section of an inverted W-shaped boiler embodying my invention.

In the several views like reference characters denote similar parts.

As shown A denotes the upper or steam 55 and water drum or drums connected with the associated lower drums B by inclined banks of tubes C arranged on each side of and enclosing between them the central furnace space or spaces D. Each bank of tubes C is partitioned into three by two baffles E and F so as to form three passes around the tubes for the gases and hot products of combustion which pass off each side of the boiler to the outlet flue G. 60 65

The tube holes in the drums A and B are so disposed as to permit the tubes of each bank to be arranged substantially symmetrically about a line indicated by XX in the drawing passing through the longitudinal axes of the upper drums A and of the lower drums B, tubes on each side of such line and equidistant therefrom being of substantially the same length and curvature. As a result, a smaller number of 70 75 forms of tube are required for each boiler and consequently a small number of spares only need be carried.

Each lower drum B is fitted with an imperforate diaphragm H so disposed as to divide the tubes of the central pass whereby a positive circulation of the water through the tubes is ensured. In the construction shown in Figure 3, consisting of a five-drum boiler with banks of tubes enclosing between them two furnace spaces D, the central mud drum B is partitioned into three separate compartments by two imperforate 80 85 diaphragms.

In case the feed system for one of the banks of tubes leading to the middle drum were disabled, the tubes would be supplied by water from the other feed chamber. For example, if the feed for the bank of tubes leading from the middle mud drum to the upper left-hand steam and water drum were disabled, the tubes of this bank would be supplied with water from the feed chambers associated with the bank of tubes leading from the middle mud drum to the upper 90 95 right-hand steam and water drum. Likewise, in case the tubes of either of these banks became overheated because of any abnormal condition, an excess of water could be fed to these tubes from the feed chamber 100 of the other steam and water drum. The system is so arranged, therefore, that the two banks of tubes balance each other in 105

normal operation, and thus leads to a satisfactory and efficient operation.

Water baffles K in the water space of the upper drum or drums, which are preferably arranged symmetrically on either side of the vertical axis, extend to or above the water line and serve to partition off the hottest water from the incoming water, which is supplied through the usual feed trough L. With the baffles thus arranged, the water flows from the chamber at the left of the baffle K, as viewed in Fig. 2, and, considering the parts at the left of the vertical center line, downwardly through the tubes connected to said chamber, into the chamber in the mud drum at the left of the imperforate diaphragm H, upwardly through the other tubes which are connected to said mud drum chamber, and to the steam and water drum between the baffles K. From the space between the baffles K, the water flows downwardly through the external down-comer I into the chamber in the mud drum at the right of the diaphragm H and upwardly through the tubes which communicate with said chamber, and which are located above the furnace D, into the steam liberating space between the baffles K in the steam and water drum. There is thus provided, in a boiler of the type described, a definite circulation, the outer tubes of the bank serving as economizer tubes, and the ascending steam and water in the tubes located above the furnace discharging into the free steam liberating space between the baffles K in the steam and water drum.

What I claim and desire to secure by Letters Patent of the United States is:—

1. A water tube boiler comprising two steam and water drums and three spaced mud drums, means for creating a circulation between said steam and water drums, and said mud drums comprising two partitions within the middle mud drum extending longitudinally thereof and dividing the same into three unconnected chambers, a bank of tubes connecting each of said steam and water drums to the outer mud drum, other banks of tubes connecting said steam and water drums to the middle mud drum, some of the tubes of each of the last mentioned banks being connected to separate chambers of the middle mud drum and other tubes being connected to a common chamber.

2. A water tube boiler comprising an upper steam and water drum, two lower mud drums, banks of tubes connecting the steam and water drum to the respective mud drums, the steam and water drum being provided with baffles extending longitudinally of the drum and at least as high as the water line, and forming a plurality of chambers therein, and means for introducing feed water to the chambers without said baffles, the lower drums being provided with imperforate diaphragms dividing each drum into two unconnected chambers to each of which a part of the tubes of the associated bank are connected, part of the tubes which communicate with one of the chambers of the mud drum being connected to the associated chamber of the steam and water drum without the baffles, and the other part of said tubes being connected to the chamber between said baffles, and downcomers connecting the middle chamber of the steam and water drum to the other chamber of each of said mud drums.

3. In a steam boiler, a furnace, an upper steam and water drum, two lower mud drums, baffles within the upper steam and water drum extending longitudinally thereof and at least as high as the water line and dividing the water space into two outer compartments and a middle compartment, each mud drum being provided with an imperforate diaphragm extending longitudinally thereof and dividing the mud drum into two unconnected chambers, feed water inlets to the outer compartments in the steam and water drum, tubes connecting each of said feed compartments to a chamber of the corresponding mud drum, tubes connecting said chamber of the mud drum to the middle chamber of the steam and water drum, external downcomers and water tubes connecting the middle compartment of the steam and water drum with the other chambers of the mud drums, the last mentioned tubes being exposed to the furnace heat.

In testimony whereof I have hereunto signed my name in the presence of two subscribing witnesses.

HENRY JOHN SUTHERLAND MACKAY.

Witnesses:

ARTHUR LASSELL,
GEORGE SUMMERS.
